Specification for Design.

Patented Mar. 12, 1912.

Application filed October 11, 1911. Serial No. 654,160. Term of patent 14 years.

To all whom it may concern:

Be it known that I, GEORGE RAINNEY, a citizen of the United States, residing at Enid, in the county of Garfield and State of Oklahoma, have invented a certain new, original, and ornamental Design for Insect-Traps, of which the following is a specification, reference being had to the accompanying drawing, forming part thereof.

In the drawing, Figure 1 is a top plan view of an insect trap showing my new design, and Fig. 2 is a side elevation of the same.

I claim:

The ornamental design for an insect trap as shown.

The foregoing specification signed at Enid, Oklahoma, this 16th day of September, 1911.

GEORGE RAINNEY.
